UNITED STATES PATENT OFFICE.

WILLIAM A. WITTBECKER, OF ST. PAUL, MINNESOTA.

INSIDE-ANGLE BEAD.

1,030,044.

Specification of Letters Patent. Patented June 18, 1912.

Application filed April 20, 1910. Serial No. 556,631.

To all whom it may concern:

Be it known that I, WILLIAM A. WITTBECKER, a citizen of the United States, and resident of St. Paul, in the county of Ramsey and State of Minnesota, have invented 5 certain new and useful Improvements in Inside-Angle Beads, of which the following is a specification.

The invention relates to supports for plaster or other like coating or finish on walls and ceilings of rooms, and particularly to such supports to be situated at or approximate to inside angles or inner corners of such rooms; and its object is to provide an 15 inside angle or inner corner bead which will readily receive in solid form and effectually hold and retain plaster or other like coating or finish, intact and in place adjacent to said inside angles or inner corners notwithstanding 20 distortion that may develop in the building from shrinkage, expansion, settling, or otherwise, also to form a fixed and definite guide or plastering edge for the plasterer or other mechanic in applying the plaster or 25 other coating or finish; these ends being accomplished at comparatively slight cost of manufacture and slight additional cost for applying in any construction work; and to these ends the invention consists in the features 30 of construction to be hereinafter more fully described and particularly pointed out in the claims.

In the accompanying drawings:—Figures 1, 2 and 3 are cross sectional views of a portion 35 of three different building constructions in which my invention is embodied as hereinafter more fully explained. Fig. 4 is a perspective view of the construction of angle bead shown in Fig. 1.

40 In constructing the angle bead a strip of sheet metal is rolled, stamped with a suitable die, or otherwise bent to form an intermediate longitudinal reentrant face a , preferably concave or substantially semi-circular in section, though its several advantages would be measurably realized by having it of reentrant angular section. The purpose of this reentrant construction is threefold, namely; first to develop sufficient elasticity to cause 45 yielding to take place in the face of the bead instead of in its walls adjacent to plaster, when the building structure becomes distorted by shrinkage, expansion or otherwise; second to leave the margins of the concave 50 face standing out as fiduciary edges for use in gaging the plaster coat; third to relieve 55

the plainness of the corner, for esthetic reasons. From the extremities of this surface a the metal is bent backward and outward at such angles that when placed in position, the 60 walls thus formed are at an obtuse angle or something more than 90° to the plaster surface to be formed, and they therefore provide under-cut limiting walls against which the plaster may build up and by which the 65 plaster may be keyed in position; said keying space however being without abrupt overhang and at such angle that the plaster readily flows into it and packs in solid mass under the spraying pressure applied 70 perpendicularly to the plaster surface. At the innermost portions of these inwardly extending walls, the bead is provided with attaching flanges a^5 , a^6 bent at such angles that they lie against the meeting walls when 75 the bead is in place, and provided with perforations a^7 , to receive nails or other securing means a^8 .

When used in lath and plaster constructions (Fig. 1) the rearwardly extending portions comprise, in addition to the plaster, walls a^1 , a^2 and attaching flanges a^5 , a^6 the off-setting walls a^3 , a^4 corresponding in width to the thickness of the lath, and adapted to stand perpendicular to the building walls and receive and firmly hold the lath at the angle of the flange a^5 , a^6 . In 80 constructions having brick on the one side and lath and plaster on the other, one only of the two members, a^3 , a^4 is provided with 85 the offsetting wall a^3 (see Fig. 2) while in brick constructions both these offsetting walls a^3 , a^4 may be eliminated, (see Fig. 3). When the angle bead is suitably secured in 90 position to an inside angle to be supported and in coincident line therewith, should any opening, spreading, or expanding, or any compression thereafter take place in such inner corner construction, it will be communicated to the concave or reentrant face 95 (a) of the bead, which by reason of its form and the form of the shoulder supporting it, will yield and compensate for such opening, spreading, expanding or compression without drawing the walls a^1 , a^2 away from the 100 plaster, or exerting pressure against the plaster that would tend to buckle, check or crack the plaster. Again, when the invention has been firmly fastened to the inside 105 angle construction as above described and as 110 illustrated by the accompanying drawings, the margins a^9 , a^{10} of the reentrant face of

the bead afford firm, accurate and true edges or guides for use in applying the plaster or other coating; the bead being so constructed and fastened over the corner that 5 the plaster or other coating when applied to the adjacent wall and meeting edges a^9 , a^{10} leaves free of plaster or other coating the surface or face (a).

I claim:

- 10 1. An inside continuous angle bead comprising attaching flanges standing in relative position corresponding to that of the walls forming the angle to be covered, plaster abutment walls standing apart and at 15 acute angles to the respective attaching flanges and thereby providing undercut plaster keying spaces, and a concave reëntrant wall providing the corner face, joining the said plaster abutment walls; each of 20 said attaching flanges and each of said plaster-abutment walls being connected by an offsetting wall; each of said plaster-abutment walls being separated from said re-entrant face by a guiding edge by which to 25 determine the surface of the plaster coating.
2. An inside continuous angle bead comprising attaching flanges standing in relative position corresponding to that of the walls forming the angle to be covered, plaster abutment walls standing apart and at 30 acute angles to the respective attaching flanges and thereby providing undercut plaster keying spaces, and a concave reëntrant face joining the said plaster abut-

ment walls, one of said attaching flanges 35 and one of said plaster-abutment walls being connected by an offsetting wall.

3. An inside continuous angle bead comprising attaching flanges standing in relative position corresponding to that of the 40 walls forming the angle to be covered, plaster abutment-walls standing apart and at acute angles to the respective attaching flanges and thereby providing undercut plaster keying spaces, and a concave reëntrant 45 face joining the said plaster abutment walls, each of said attaching flanges and each of said plaster-abutment walls being connected by an offsetting wall.

4. An inside continuous angle bead comprising attaching flanges standing in relative position corresponding to that of the walls forming the angle to be covered, plaster abutment walls standing apart and at acute angles to the respective attaching 55 flanges and thereby providing undercut plaster keying spaces, and a concave reëntrant face joining the said plaster abutment walls, one of said attaching flanges and one of said plaster-abutment walls being connected by 60 an offsetting wall, said plaster abutment walls and the reëntrant face being separated by a guiding edge or margin by which to determine the surface of the plaster coating.
